United States Patent Office

Des. 221,776
Patented Sept. 7, 1971

221,776

BOOKCASE

Douglas Deeds, San Diego, and Barry L. Rosengrant, Los Angeles, Calif., assignors to Architectural Fiberglass, Inc., Los Angeles, Calif.

Filed Jan. 19, 1970, Ser. No. 20,968

Term of patent 14 years

Int. Cl. D6—01

U.S. Cl. D33—2

FIG. 1 is a perspective view of the bookcase embodying our new design as taken from the front and to one side; FIG. 2 is a perspective view taken from the back and from the other side;

FIG. 3 is a top plan view;

FIG. 4 is a right side elevational view; and

FIG. 5 is a left side elevational view.

We claim:

The ornamental design for a bookcase, substantially as shown.
